CLAIM

The ornamental design for a reflective golf swing and putting practice aid, as shown and described.

DESCRIPTION

FIG. 1 is a front perspective view of a reflective golf swing and putting practice aid showing my new design;

FIG. 2 is a top plan view thereof;

FIG. 3 is a bottom plan view thereof;

FIG. 4 is a bottom plan view of a second alternate embodiment, the top plan view being identical to FIG. 2;

FIG. 5 is a front elevation view of both embodiments; and,

FIG. 6 is a right side elevation view thereof, the opposite side being a mirror image.
